(57) **CLAIM**

I claim the ornamental design for a fan clamp, as shown and described.

DESCRIPTION

FIG. 1 is a top side perspective view of a fan clamp of the present invention.

FIG. 2 is a bottom side perspective view of a fan clamp of the present invention.

FIG. 3 is a front elevation view of the fan clamp of FIG. 1. FIG. 4 is a rear elevation view of the fan clamp of FIG. 1. FIG. 5 is a side elevation view of the right side of the fan clamp of FIG. 1.

FIG. 6 is a side elevation view of the left side of the fan clamp of FIG. 1.

FIG. 7 is a top plan view of the fan clamp of FIG. 1; and, FIG. 8 is a bottom plan view of the fan clamp of FIG. 1. In the drawings, the broken lines depict environmental structure that form no part of the claimed design.
